LOCK

Joseph Kaufman, New York, N. Y.

Application September 29, 1944, Serial No. 556,393

5 Claims. (Cl. 70—97)

1

This invention relates to locks. It is particularly directed to a key actuated lock.

An object of this invention is to provide an improved key actuated lock such as may be employed for locking folding gates and the like articles.

In former foldable gate locks such as described in Patent No. 1,651,394, issued December 6, 1927, the lock includes a bolt which projects from a housing and engages a keeper. When the gate is open a portion of the bolt is exposed. It has been found that vandals or thieves often tamper with the exposed bolt or break it so that the gate cannot be locked. It is hence another object of this invention to provide a lock of the character described comprising a housing provided with a chamber in which the bolt is mounted, and a keeper having a tongue insertable into the chamber when the lock is open, and said bolt being adapted to be rotated to a position where it engages the inserted tongue to lock the keeper against withdrawal from the chamber. With such construction the bolt is wholly housed within the housing and cannot be tampered with or broken to thereby prevent locking of the lock.

Yet another object of this invention is to provide a strong and durable lock of the character described which shall be relatively inexpensive to manufacture, sure and positive in operation, rugged in construction, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is an elevational cross-sectional view of a lock embodying the invention with parts in cross-section;

Fig. 2 is a cross-sectional view taken on line 2—2 of Fig. 1;

Fig. 3 is a front elevational view of the lock housing;

Fig. 4 is a rear elevational view thereof;

Fig. 5 is a rear perspective view of the rotary bolt;

Fig. 6 is a front perspective view thereof;

Fig. 7 is a perspective view of the key cylinder;

Fig. 8 is a cross-sectional view taken on line 8—8 of Fig. 1;

Fig. 9 is a view similar to Fig. 8 but showing the bolt in unlocked condition; and

Fig. 10 is a front elevational view of a folding

2

gate provided with a lock embodying the invention.

Referring now in detail to the drawing, 10 designates a lock embodying the invention which may be used in a folding gate 11. The folding gate 11 comprises gates 12 and 13 of usual construction. The gates 12 and 13 comprise vertical end members 14 and 15 which are moved toward or away from each other to close or open the gate. 10 The lock 10 comprises a keeper 16 on member 14, and a housing 18 on member 15. Housing 18 may comprise a prismatic block of metal fixed to member 15 by a pair of rivets 18a.

The keeper 16 is made of a flat piece of metal 15 and may be riveted, welded or otherwise attached to gate member 14. The keeper 16 has a portion 20 projecting beyond the gate member 14. Said portion 20 is formed with a T-shaped slot 21 forming a pair of symmetrical, opposed, hooked tongues 23 and 24 as shown in Fig. 1 of the drawing.

The housing 18 is formed with a horizontal opening 25, the axis of which is along the center line of keeper 16. The opening or bore 25 extends to the rear end of the housing but terminates short of the front end thereof. At the front end of opening 25 is an opening 26 co-axial therewith. The opening 26 has a diameter smaller than the diameter of opening 25. Housing 18 is 25 also formed with a vertical slot or opening 28 extending above and below the bore 25 and opening 26. Opening 28 extends to the front surface of housing 18 but terminates short of the rear surface of said housing.

35 It will now be understood that adjacent the front surface of the housing are formed a pair of diametrically opposed flanges or shoulders 30 for the purpose hereinafter appearing.

Disposed within bore 25 is a key cylinder 32 40 of any suitable construction. Within the key cylinder is a rotary member 33 formed with a flat forwardly projecting tongue 34. Upon turning the key 35 to open the lock, tongue 34 is moved to vertical position and when the key is turned to lock the lock, tongue 34 is turned to horizontal position. Key cylinder 32 may be fixed within bore 25 by means of a pin 37 pressed through an opening 38 in one side of the housing.

Rotatably mounted within the forward end of bore 25 and in front of the key cylinder 32 is a bolt 40. Bolt 40 comprises a stem 41 formed with a transverse slot 42 at its rear end receiving therethrough the tongue 34. At the front end of the stem 41 is an annular enlarged flange 43 formed at diametrically opposite sides thereof with notches 44. It will be noted that bolt 40 is located between the rear surface 28a of slot 28 and flanges 30. Flange 43 is adapted to contact the flanges 30. Flange 43 is cylindrical and therefore rotatably mounts the bolt within the front end of

bore 25. Lips 30 prevent the bolt from coming out of the housing.

It will be noted that the notches 44 are aligned with the transverse notch 42. Thus when the lock is locked, the notches 44 as well as the notch 42 are in a horizontal plane. When the lock is unlocked both the notches 44 and notch 42 are in vertical position.

Referring now to Fig. 1 of the drawing, it will be noted that the hooks 23 and 24 can enter the slot or chamber 28 when the lock is unlocked and the notches 44 are in vertically aligned positions. When the tongues 23, 24 are inserted into slot 28 the head or flange 43 of the bolt will be disposed within the slot 21 of the keeper. Upon then locking the lock, bolt 40 will be rotated to the position shown in Figs. 1, 2 and 8 of the drawing, bringing the flange 43 into engagement with the hooked portions of tongues 23, 24. The lock is then locked and the keeper cannot be withdrawn from the lock.

To open the lock, the key is turned to again bring notches 44 to vertically aligned positions, thereby bringing the tongues into registry with the notches to permit the keeper to be withdrawn from slot and chamber 28.

It will now be understood that the bolt 40 is wholly housed within slot or chamber 28 and opening 25. The bolt is thus wholly within the housing and does not project from the housing so that it cannot be broken or bent.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A lock comprising a housing formed with a bore, a key cylinder within said bore, said housing being formed with a slot communicating with the bore, a bolt rotatably mounted within said bore, means on the housing to retain the bolt within said housing, said bolt being formed with a reduced stem, and an enlarged flange on said stem, said flange being formed with a pair of opposite notches, a keeper formed with a T-shaped slot providing a pair of symmetrically disposed, hooked tongues insertable into the slot in the housing when the slots in the flange register therewith, and means on the key cylinder to rotate said bolt to disalign the slots in the bolt relative to said tongues.

2. In a lock, a housing formed with a bore extending to the rear end of the housing and terminating short of the front end of the housing, said housing being formed with an opening at the front end thereof registering with the bore and of smaller diameter than said bore, and said housing being furthermore formed with a slot extending to both sides of said bore and opening and extending to the front end of the housing but terminating short of the rear end of the housing, said housing thereby being formed with a pair of opposite lips at the front end thereof, a keeper formed with a T-shaped slot providing a pair of hooked, symmetrically disposed tongues on opposite sides of said T-shaped slot, insertable into the slot in the housing, a

key cylinder fixed within said bore, a member controlled by said key cylinder and formed with a tongue, a bolt within the front end of said bore, said bolt having a rearwardly extending stem formed with a transverse groove receiving the tongue on the cylinder, said bolt being formed with an enlarged annular flange contacting said lips, said flange being formed with a pair of oppositely disposed notches aligned with said groove, the hooked tongues of said keeper being adapted to move through said notches into said slot in the housing when the bolt is in such position that the notches in its flange are in alignment with the slot in the housing, said bolt being rotatable by means of a key inserted into the cylinder to disalign the notches in the bolt relative to the hooked tongues, whereby the flange of the bolt engages the hooked tongues to prevent withdrawal of the keeper from the housing.

3. A lock comprising a housing formed with a chamber, a bolt having a pair of diametrically disposed notches, said bolt being wholly received with the chamber in the housing, a keeper having a pair of inwardly extending hooks movable into said chamber when the notches in the bolt are aligned with said hooks, and means to rotate said bolt to a position where the notches are not aligned with said hooks, and said bolt having means to engage said hooks in the locked position of said bolt.

4. A lock comprising a housing formed with a bore, a key cylinder within said bore, said housing being formed with a slot communicating with the bore, a bolt rotatably mounted within said bore, means on the housing to retain the bolt within said housing, said bolt being formed with a reduced stem, and an enlarged flange on said stem, said flange being formed with a notch, a keeper formed with a hooked tongue insertable into the slot in the housing when the slot in the flange registers therewith, and means on the key cylinder to rotate said bolt to disalign said slot in the bolt relative to said tongue, whereby to engage said flange of said bolt with said tongue.

5. A lock comprising a block, said block being formed with a bore extending to a surface thereof, said block being formed with a slot communicating with the bore and extending to an offset surface of the block, said block being formed with flanges on opposite sides of said slot at said offset surface, a key cylinder fixed within said bore, a bolt rotatably mounted within said bore, and adjacent said slot, said bolt being formed with an annular flange adapted to contact the flanges of said block, the flange of said bolt being formed with a notch, a keeper having a hooked tongue insertable into said slot when the slot in the flange of the bolt registers therewith, and means on the key cylinder to rotate said bolt to disalign the notch in the flange of the bolt relative to said tongue.

JOSEPH KAUFMAN.
